UNITED STATES PATENT OFFICE.

SAMUEL S. ROSE, OF SAN JOSE, CALIFORNIA.

ELECTROCHEMICAL AMALGAMATOR.

1,186,335.

Specification of Letters Patent. Patented June 6, 1916.

Application filed March 25, 1915. Serial No. 16,948.

To all whom it may concern:

Be it known that I, SAMUEL S. ROSE, a citizen of the United States, residing at San Jose, in the county of Santa Clara, State of California, have invented certain new and useful Improvements in Electrochemical Amalgamators; and I do declare the following to be a clear, full, and exact description of the same, reference being had 10 to the accompanying drawings, and to the characters of reference marked thereon, which form a part of this application.

This invention relates to improvements in paraphernalia and structure for amalgamating the precious metals found in talc or similar minerals and is especially designed as a means or structure for carrying out the steps of the process of electro-chemical amalgamation wherein the crushed ores are 20 treated with the mercury in the presence of electricity, the object of the present invention being to produce a simple and efficient means for carrying out such process.

A further object of the invention is to 25 produce a simple and inexpensive device and yet one which will be exceedingly effective for the purposes for which it is designed.

These objects, I accomplish by means of 30 such structure and relative arrangement of the parts as will fully appear by a perusal of the following specification and claims.

On the drawings, similar characters of reference indicate corresponding parts in 35 the several views.

Figure 1 is a top plan view of the complete amalgamator. Fig. 2 is a sectional view taken on a line B—B of Fig. 1. Fig. 3 is a detached fragmentary view in section 40 of one of the drag sweepers taken on a line Y—Y of Fig. 1. Fig. 4 is a sectional view of one of the supporting rollers for the drag sweepers taken on a line X—X of Fig. 2. Fig. 5 is a fragmentary sectional 45 view showing the outlet opening from the amalgamating receptacle illustrating the structure for varying the size of the opening.

Referring now more particularly to the 50 characters of reference on the drawings, the numeral 1 designates any suitable frame or support for the device on which is suitably supported the amalgamating receptacle

which consists primarily of a central distributing receptacle 1^a having a conical-shaped distributing base 2. The sides of the said member 1^a are spaced slightly from the bottom 2 at the lower edge, as at 3, with intermediate supporting feet 4. The mineral delivered into the receptacle 1^a passes 55 through the opening 3 into an outer annular chamber or receptacle 5. Projecting inwardly on the upper edges of the member 5 are runways or guides 6.

The numeral 7 designates a pulley, adapted 65 to be driven by any suitable source of power, which in turn drives a shaft 8 having on its end a beveled gear 9 meshing with another beveled gear 10 on a vertical shaft 11 secured to which is a pinion 12, 70 the pinion proper being insulated from the shaft 11 against the conduction of the electrical current by means of suitable insulation 13. The pinion 12 intermeshes with an annular internally geared pinion 14 bolted 75 to which are a plurality of frames 15 having a roller 16 journaled in each end, such rollers bearing on the members 6. These said rollers 16 are suitably insulated from the members 15 by means of suitable insulation 80 members 17. On each of the members 15 are a pair of downwardly projecting arms 18, one extending obliquely on one side of its frame 15 and the other on the other side, substantially as shown in Fig. 1. On every 85 third pair of arms 18 is secured a sweeper bar 19 and bolted to the same by means of rods 20 are drag bars 21 curved at their forward edges, as at 22. On the other arms 18 are secured sweepers 23 having a plurality of teeth 24 along their lower edges. From a source of electrical energy 25, a wire 26 leads to the bottom of the receptacle 5. Secured to and insulated from the side wall of the receptacle 1^a is a frame 14^a 90 which extends upwardly and arches over the member 14 where it is provided with a small roller 14^b bearing on the member 14. Connected with this member 14 is another wire 27 which leads back to the source of 95 electrical energy 24. In this manner a circuit is completed through the source 25, through the wire 26, through the member 5, through the slight space 28, between the bottom of the member 5 and the lower edges 100 of the finger members 24 or lower edges of

the members 19, thence through the members 19 and 23, thence through the arms 18, frames 15, and member 14, roller 14^b, bracket 14^a, and wire 27 to the source 25, attention 5 being called to the insulation between the rollers 16 and the frames 15 and between the pinion 12 and the shaft 11.

In practice, power is applied in any suitable manner to the member 7, which, 10 through the connection shown, rotates the member 14 which in turn carries the members 15 with a rotary motion in the direction of the arrow shown in Fig. 1. The pulverized talc, which is previously mixed 15 with a salt to cut its sleek greasy consistency, is fed into the receptacle 1^a where it is equally distributed by the member 2 to flow through the opening 3 into the member 5, the bottom of which is suitably 20 covered with quicksilver. The action of the drag sweeper 19 and its drag 21 is to work and force the pulverized talc as close toward the bottom of the member 5 as possible. This operation brings the crushed 25 ores into contact with the mercury in the presence of electricity with results common to the art.

As is well known to those skilled in the art, the precious metals found in the talc, 30 while of a very high grade, are very flaky and the talc itself is so sleek and greasy that it acts as an insulation against amalgamation. This condition I break up by the addition of the salt to the talc and by the 35 bringing of the mercury into contact with the talc in the presence of electricity. The residue, left after the amalgamation in the receptacle 1^a, passes out of an opening 29 at one side of the member 5 and thence over 40 a silver-plated apron 30. The width of this opening can be varied by laying shims 29^a, of different lengths, on the top of the lower edge of the opening and securing the same by small screws 29^b. In this way, the 45 depth of the mineral in the amalgamating receptacle may be varied accordingly to provide the best efficiency in the amalgamation. The opening 29 extends approximately half way around the circumference 50 of the receptacle 5 and delivers first into a distributing channel 29^c, thence to the apron 30.

Due to the fact that the amalgamation takes place in the member 5 while the elements are held in suspension by the action 55 of the electrical current, it is possible that some portion of the amalgam may pass out of the opening 29 and upon the apron 30 with the residue of the mineral, and in order to save this, I provide a counter-electro movement to that which takes place 60 in the amalgamator which is constructed and operates as follows: Above the apron 30 I provide a plate 31 on which are a plurality of downwardly depending points 32

arranged slightly obliquely with respect to the horizontal plane of the apron 30. From a source of electrical energy 33, a wire 34 leads to the plate 31, while a wire 35 leads from the apron 30 back to the source 33. 70 This completes the circuit from the source 33 through the wire 34, through the plate 31, through the points 32, through a jump space 36 between the points 32 and the apron 30, thence through the wire 35, back 75 to the source 33. By means of this electrical current, any amalgam which may be passing over the apron 30 will be moved downwardly into contact with the silver-plated apron 30 with the result that the same is 80 saved from passing with the valueless residue off of said apron.

From the foregoing description it will readily be seen that I have produced such a device as substantially fulfills the objects of 85 the invention as set forth herein.

While this specification sets forth in detail the present and preferred construction of the device, still in practice, such deviations from such detail may be resorted to as 90 do not form a departure from the spirit of the invention, as defined by the appended claims.

Having thus described my invention, what I claim as new and useful and desire 95 to secure by Letters Patent is:—

1. A device of the character described comprising the combination with an amalgamating receptacle containing mercury, of sweeper bars movable within the receptacle, 100 drag bars rearwardly spaced from the sweeper bars and connected therewith, both the sweeper and drag bars being in close proximity to the surface of mercury in the bottom of the receptacle, means for supporting and actuating the sweeper bars, a source of electricity, and connections between the bars and the receptacle to such source of electricity, as described.

2. A device of the character described 110 comprising the combination with an amalgamating receptacle containing mercury, of sweeper bars movable within the receptacle, drag bars rearwardly spaced from the sweeper bars and connected therewith, the 115 forward edges of such drag bars being curved, the curvature of said drag bars being horizontal transversely to the receptacle, both the sweeper and drag bars being in close proximity to the surface of mercury 120 in the bottom of the receptacle, means for supporting and actuating the sweeper bars, a source of electricity, and connections between the bars and the receptacle to such source of electricity, as described.

3. A device of the character described comprising an annular receptacle having inwardly projecting runways on its inner and outer circumference, rollers mounted on said runways, frames mounted on said 125

rollers and insulated therefrom, an internal gear secured to said frames, means for driving said gear, sweepers mounted on said frame and movable adjacent the bottom of said receptacle, a frame secured to the receptacle and insulated therefrom and arching over said gear, a roller on said frame bearing on said gear, a source of electrical energy, wire connections from said source of electrical energy to said last named frame 10 and from said receptacle to said source of electrical energy, as described.

SAMUEL S. ROSE.
